UNITED STATES PATENT OFFICE.

WILLIAM VANDERMAN, OF WILLIMANTIC, CONNECTICUT.

INSERTIBLE FITTING FOR SOIL-PIPES.

No. 799,954.

Specification of Letters Patent.

Patented Sept. 19, 1905.

Application filed April 8, 1905. Serial No. 263,606.

To all whom it may concern:

Be it known that I, WILLIAM VANDERMAN, a citizen of the United States, and a resident of Willimantic, in the county of Windham 5 and State of Connecticut, have invented a new and Improved Insertible Fitting for Soil-Pipes or the Like, of which the following is a specification.

My invention relates more especially to the 10 class of devices used in the plumbing of buildings; and the object of my invention is to provide a device by means of which a section of pipe may be readily removed when desired and a new section supplied to take the place 15 of the removed section; and a further object of the invention is to provide means for inserting the section of pipe and firmly securing it in place. A form of device in the use of which these objects may be attained is illustrated in the accompanying drawings, in which—

Figure 1 is a view, partly in section, of part of a line of soil-pipe, showing the application of my invention and before the parts have 25 been secured in place. Fig. 2 is a similar view showing the pipe-sections secured in position. Fig. 3 is a detail view showing the thimble in side elevation as applied to the end of a pipe and before it has been secured in 30 place. Fig. 4 is a top view of the same. Fig. 5 is a detail view showing a modified form of thimble. Fig. 6 is a top view of the same. Fig. 7 is a detail view showing another modification of the invention. Fig. 8 35 is a view in section through the ring shown in Fig. 7. Fig. 9 is a view showing the application of the latter-described form of the invention.

It often becomes necessary in a building to 40 remove a section of soil or other pipes, as for the purpose of supplying a branch or where a section has become defective. In the older methods several sections of the pipe were disturbed to accomplish this result, and to ob- 45 viate this objection various means have been devised. Such means, however, are objectionable from the fact that more or less space is left between the abutting ends of two sec- 50 tions with a result that the joint is not as strong and durable as would be desired.

By the employment of my invention I have provided means for extending a section of pipe after it has been placed in position, so that a section may be removed and renewed, 55 and by means of the extension, which forms practically an integral part of the section of

pipe, the ends of the two sections are, in effect, brought close together, abutting against each other, so that the resultant joint is, in effect, practically as strong as when the line 60 of piping was first constructed.

In the accompanying drawings a portion of a line of waste-pipe of a building is illustrated, including a portion 1 and a portion 2. These when the line of piping is originally formed 65 are joined by a section similar to those illustrated at 1 and 2. It is when such a section is removed for any purpose whatever that my invention becomes applicable. It will of course be understood that the improved in- 70 sertible section may be plain—that is, free from branches or T's or may include such elements.

My improved insertible fitting includes as the essential elements an insertible section 75 4 and an extension-thimble 9. This insertible section is provided with a spigot end 7 for engagement with the section 2 of the main and has an elongated hub for the reception of the thimble 9. This extension-thimble is used for the purpose of extending a section 3 of the line of piping, the spigot end 6 of which is inserted in the hub 8 and elongated, as by means of the thimble 9. This section 3 of the pipe is of the ordinary con- 80 struction, having the spigot end 6 and the hub end 5, as used in the remainder of the line of piping.

It will be understood that in furnishing my improved insertible fitting the new construc- 90 tion consists merely in the insertible section of peculiar construction and the thimble, the remaining parts being of old and well-known construction.

The thimble 9 is adapted to fit closely about 95 the spigot end of the section 3, and the thimble may be formed in sections, as shown in Figs. 3 and 4 of the drawings, although such construction is not indispensable. The lower end of the thimble is constructed to closely 100 fit the spigot end 6 of the section 3 of the line, and a space 10 may be primarily left between the inner surface of the upper end of the thimble and the outer surface of the section 3, although this is not essential to my 105 invention. The construction of the thimble in sections is especially applicable where the section 3 of the line of piping contains a rib at the extremity of the spigot end, as shown in Fig. 1; but it is obvious that the construc- 110 tion herein shown may be departed from to a considerable extent so long as there is em-

bodied in the construction means for extending one of the sections of the line of piping, said extension being adapted to closely fit the end of said section, there being also means to receive and provide for extending said section.

In placing my improved fitting in position the thimble is placed about the spigot end of the section 3, and said end and the thimble are inserted in the elongated hub 8, as shown in Fig. 1 of the drawings. The thimble rests upon the shoulder 11, and the upper section is extended or moved upward to the position shown in Fig. 2 of the drawings. Oakum is then packed into the hub 8 about the thimble, as shown at 12 in Fig. 2 of the drawings, this oakum being packed in any well-known manner. In this operation the upper end of the thimble 9, especially where the space 10 is present, is forced tightly against the outer surface of the section 3. The thimble may be so constructed that its outer surface and the inner surface of the hub 8 will be located at an angle with each other. This provides a thimble practically closed at the bottom and tapered to a smaller diameter toward the top. Lead is then filled into the space between the section 3 and the hub 8, as shown at 13 in the drawings. It will be seen that when the joint is finished the thimble has been tightly secured in place and forms practically an extensible integral part of the section 3. The tapered space between the thimble and hub 8 affords means for causing the thimble to tightly grasp the section 3, and a firm and secure joint is thus obtained, practically as firm and strong as are the joints between the other sections of the line.

In Fig. 5 of the drawings the tapered surface by means of which the spigot-section of the fitting is grasped is formed between the thimble and the section 3, the thimble 14 in this form of device having a beveled surface 15, between which and the outer surface of the section 3 the oakum is tightly packed.

As the oakum is forced downward into the narrow space the spigot-section 3 is tightly grasped, as before, and a secure joint thus obtained, the thimble being forced into tight contact with the inner wall of the hub 8.

In the form of device shown in Figs. 7, 8, and 9 of the drawings the hub-section 16 is provided with a coarse thread 17, tapering from the mouth of the elongated hub inward toward the bottom. A ring 18, preferably formed in sections and having an outer thread fitting the thread in the hub, is placed about the lower end of the spigot-section 19, and then, as by means of a spanner-wrench inserted in the holes 20, the ring is screwed tightly to place, the tapered threaded surface on the hub enabling it to tightly grasp the outer surface of the section 19 and hold it in place. Oakum and lead are then packed into the space between the hub 16 and the

spigot-section of the fitting in the usual 65 manner.

What I claim as my invention, and desire to secure by Letters Patent, is—

1. A renewable pipe-fitting for a system including a section with an opening the same size as that of the system, and having an elongated hub, a section with a spigot end to project within said hub and a flexible extension-ring interposed between the two sections and providing a beveled surface whereby said spigot end is grasped and securely held in place. 70

2. A renewable pipe-fitting for a system including a section with an opening of the same size as that of the system and having an elongated hub, a section with a spigot end to project within said hub, an extension-ring having one wall separated along its length and interposed between said sections and providing a beveled surface whereby said spigot 85 end is grasped and securely held in place. 80

3. A renewable pipe-fitting for a system including a section with an opening of the same size as that of the system and having an elongated hub, a section with a spigot end to project within said hub, and a sectional extension-ring interposed between the sections and providing a beveled surface whereby said spigot end is grasped and securely held in place. 90

4. A renewable pipe-fitting for a system including a section with an opening of the same size as that of the system and having an elongated hub, a section having a spigot end to project within said hub, and a flexible ring 100 interposed between the sections and providing a beveled surface for the reception of a packing whereby said spigot end is grasped and securely held in place. 95

5. A renewable pipe-fitting for a system including a section with an opening of the same size as that of the system and having an elongated hub, a section with a spigot end to project within said hub, and a flexible extension-ring having a wall separated along its length 110 and interposed between the sections and having a beveled surface to receive a packing whereby said spigot end is grasped and securely held in place. 105

6. A renewable pipe-fitting for a system including a section having an opening of the same size as that of the system and with an elongated hub, a section having a spigot end to project within said hub, and a sectional extension-ring interposed between the sections and providing a beveled surface for the reception of a packing whereby said spigot end is grasped and securely held in place. 115

7. A renewable pipe-fitting including a hub-section, a section with a spigot end to project within said hub-section, a flexible thimble interposed between the sections and constructed to provide a beveled surface between the thim- 120 125

ble and hub-section for the reception of a packing whereby the thimble is forced against the spigot end to grasp and securely hold it in place.

5 8. A renewable pipe-fitting including a hub-section, a section with a spigot end to project within said hub-section, a split thimble interposed between the sections and providing a beveled surface for the reception of packing 10 whereby the thimble is forced against and tightly grasps the spigot end.

9. A renewable pipe-fitting including a hub-section, a section having a spigot end to project within the hub-section, an expansible 15 thimble to rest upon the shoulder in said hub and providing a beveled surface for the reception of a packing to force the thimble to grasp and tightly hold the spigot end in place.

10. A joint for a renewable fitting including 20 a hub-section, a section with a spigot end to project within said hub-section, a flexible thimble interposed between the two sections and providing a beveled surface between its outer wall and the inner wall of the hub-section, and 25 a packing forced between the outer wall of the thimble and the inner wall of the hub-section whereby the thimble is forced tightly against to grasp and securely hold the spigot end in place.

30 11. A joint for a renewable pipe-fitting including a hub-section, a section having a spigot end to project within said hub-section, a split thimble located between the two sections, and a packing forced between the outer surface of 35 the thimble and the inner surface of the hub-section whereby the thimble grasps and securely holds the spigot end in place.

12. A renewable pipe-fitting for a system including two sections with fluid-conducting 40 passages therethrough of the same diameter, and one section formed to receive the end of the other section, and a thimble fitting the end of one of the sections and forming an adjustable extension thereof.

45 13. A renewable pipe-fitting for a system in-

cluding a hub-section and a section with a spigot end to project with the hub-section, said sections having fluid-conducting passages therethrough of the same diameter, and a thimble located upon the end of the hub-section 50 and forming an adjustable extension thereof.

14. A renewable pipe-fitting for a system including a section with an elongated hub, a section having a spigot end to project within said hub, said sections having fluid-conducting 55 passages therethrough of the same diameter, and a thimble fitting upon said spigot end to form an adjustable extension thereof to rest upon the shoulder formed in said elongated hub.

15. An insertible section for a system said 60 section having a fluid-conducting passage therethrough of the same diameter as that of the parts to be joined and provided with an elongated hub, and a thimble to adjustably extend a section to be secured within said hub: 65

16. An insertible section for a system having a fluid-conducting passage therethrough of the same diameter as that of the sections to be united and provided with an elongated hub, and an expansible thimble to adjustably 70 extend a section to be secured within said hub.

17. An insertible section having a fluid-conducting passage therethrough of the same diameter as that of the parts to be united and provided with an elongated hub, and a thimble extension to prolong a section to be secured within said hub, said thimble providing 75 a tapered space between its outer surface and the inner surface of the elongated hub.

18. An insertible section having a fluid-conducting passage therethrough of the same diameter as that of the parts to be united and provided with an elongated hub and an annular adjustable extension member to be fitted within said hub and arranged to rigidly secure 80 it to the end of a section to be secured therein. 85
